UNITED STATES PATENT OFFICE.

CHARLES FRANCIS JENKINS, OF WASHINGTON, DISTRICT OF COLUMBIA, ASSIGNOR TO
SINGLE SERVICE PACKAGE CORPORATION OF AMERICA, OF NEW YORK, N. Y., A
CORPORATION OF NEW JERSEY.

CLOSURE FOR RECEPTACLES.

970,926.

Specification of Letters Patent. Patented Sept. 20, 1910.

Application filed February 1, 1910. Serial No. 541,398.

To all whom it may concern:

Be it known that I, CHARLES FRANCIS JENKINS, a citizen of the United States, residing at Washington, in the District of Columbia, have invented certain new and useful Improvements in Closures for Receptacles; and I do hereby declare the following to be a full, clear, and exact description of the invention, such as will enable others skilled in the art to which it appertains to make and use the same.

This invention relates to bottom closures for receptacles and has for its object the production of a closure of this nature which will be exceedingly cheap to manufacture, and to put into place; and which, when once positioned, will be efficient in action.

To these ends the invention consists in the novel details of construction and the combination of parts more fully hereinafter disclosed, and particularly pointed out in the claims.

Referring to the accompanying drawings forming a part of this specification in which like numerals refer to like parts in all the views, Figure 1 is a longitudinal sectional view of a vessel showing a portion of the bottom closure in place and diagrammatically illustrating a means for placing the remaining portion of the closure in position; Fig. 2 is a sectional view of a vessel after the bottom closure is in place; and Figs. 3 and 4 are detail sectional views illustrating features to be referred to hereinafter.

1 represents any suitable vessel body, preferably of a cylindrical form; and 2 a lower half of the bottom closure which, if the body 1 is circular in cross section, will be in the form of a disk. The portion 2, is shaped to fit the interior of the body 1, is slightly larger than the same, and is dished as illustrated while being placed in the body. 3, in Fig. 1, illustrates the other portion of the closure which is likewise slightly larger than the interior of the vessel 1; and 4 is any suitable means as a shaping die through which the said portion 3 may be forced by the plunger 5 and dished as indicated in Fig. 2.

It is preferred to place a small portion of glue 6, or other fastening means, upon the

closure 2 before it is inserted into the body 1 so that when the portion 3 is forced through the said body into the position shown in Fig. 2, the two portions 2 and 3 will be firmly held together. After the said portions 2 and 3 are in position as indicated they will effectually resist motion in either direction for that their respective edges 7 and 8 will tend to bite into the walls of the body 1, and thereby tend to seat themselves more firmly than before. In Fig. 3 there is illustrated the effect of pressure from the inside of the body tending to force the closure outward, and a bend 10 in the portion 2 is of such a nature as to force the edge 8 outward and firmly against the inside of the body 1. In the same way should pressure be applied in the direction of the arrow shown in Fig. 4, the bend 11 would be formed in the portion 3 and the edge 7 would likewise be forced firmly against the interior of the body.

It is evident that the body 1 may be made of any suitable material, that its interior may be of any desired shape, and that the portions 2 and 3 may be readily stamped out of any suitable material and of a shape to conform to that of the body 1.

What I claim is:—

1. In a vessel the combination of a body portion, and a closure comprising oppositely dished portions the extreme edges of which fit the interior of said body portion; substantially as described.

2. In a vessel the combination of a body portion, and a closure comprising oppositely dished portions the extreme edges of which fit the interior of said body portion, and means for securing said portions together; substantially as described.

3. In a paper vessel the combination of a body portion, and a pair of oppositely dished disks closely fitting the interior of said body portion and glued together; substantially as described.

In testimony whereof, I affix my signature, in presence of two witnesses.

CHARLES FRANCIS JENKINS.
